Primary Examiner — Lilyana Bekic*Assistant Examiner* — Mary Shannon Malley(74) *Attorney, Agent, or Firm* — Juan Carlos A. Marquez; Marquez IP Law Office, PLLC(57) **CLAIM**

The ornamental design for a UVC LED toilet sterilizer, as shown and described.

DESCRIPTION

FIG. 1 is a perspective view of a UVC LED toilet sterilizer, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view of another side thereof.

The broken lines depict portions of the UVC LED toilet sterilizer that form no part of the claimed design.

1 Claim, 5 Drawing Sheets(56)
